MIXING LIQUIDS

Edward Schmidt, Methuen, Mass., assignor to
 Lawrence Pump and Engine Co., Lawrence,
 Mass., a corporation of Massachusetts

Application September 16, 1939, Serial No. 295,190

8 Claims. (Cl. 259—96)

This invention relates to an improvement in a mixing device and more particularly in a device of the type employed in the treatment of heavy non-diffusible liquids or of liquids which are to be emulsified such as tar, asphalt, paint, emulsions and the like.

The treatment of these liquids by a device embodying this invention may involve either the blending of different liquids by breaking up those 10 very small particles which are not visible to the naked eye and thoroughly intermingling them or the creating in the liquid mass of a violent disturbing action. The second treatment may or may not be accompanied by the first. In order 15 to differentiate between such treatments it is customary in the industry to apply the term "mixing" to the first treatment and the term "agitating" to the second. For the purpose of describing this invention, however, the term 20 "mixing" is used throughout the specification to include both treatments and not in its limited sense.

The primary object of this invention is to provide a device by which such liquids are mixed to 25 bring them into a uniform homogeneous condition, such device acting to withdraw the liquid from the bottom of a container and return such withdrawn liquids to the main body thereof at two or more levels, the withdrawn liquid being 30 returned to the container under such pressure that it displaces the liquid therein at such levels.

Further objects of the invention reside in the 35 structure of the device and the provision of means for breaking up the very fine particles of the liquid, for withdrawing the liquid at the bottom of the container, for preventing the formation of an inverted vortex which interferes with the normal operation of the device, for returning graduated quantities of the withdrawn liquid to the containers at various levels, and for preventing the escape of liquids from the container during the agitation thereof.

These and other objects will appear from a 40 consideration of the following description of certain embodiments of the invention and of the drawings which form a part thereof, and in which:

Fig. 1 is a longitudinal sectional view of a mixer embodying this invention;

Fig. 2 is an enlarged plan view of the base and impeller of such mixer;

Fig. 3 is a view in side elevation of the base;

Fig. 4 is a cross-sectional view taken along the line 4—4 in Fig. 2;

Fig. 5 is a bottom plan view of the impeller;

Figs. 6 and 7 are cross-sectional views taken along the lines 6—6 and 7—7 in Fig. 1;

Figs. 8 and 9 are sectional views illustrating various ways of supporting the upper end of the mixer shaft;

Fig. 10 is a sectional view similar to Fig. 1, with parts broken away, illustrating another embodiment of the invention;

Fig. 11 is a view in elevation of another embodiment of this invention;

Fig. 12 is an enlarged longitudinal section thereof;

Fig. 13 is a plan view of a portion of the device with parts shown in section; and

Fig. 14 is a bottom plan view of one element thereof.

The mixer 20 shown in Figs. 1 to 7 inclusive 20 comprises a shaft 21 carrying an impeller 22 at the bottom end and driven by a motor 23 acting upon the upper end of the shaft and suitably connected thereto. The impeller 22 is received in a base 24 and the shaft 21 is surrounded by a tubular casing 25. The motor 23 rests upon the top of the casing 25 and the base 24 is removably attached to the bottom of the casing. The shaft 26 is suspended from the motor shaft 26 and supported for rotation adjacent its lower end in a bearing 27 carried by a cross-rib 28 integral with the casing 25.

The base 24 is provided with a central pocket 30 30 surrounded by an annular wall 31. At the under side of the base are provided legs 33 on which the mixer is supported.

Through the wall 31 extend ports 34 which lead 35 from the pocket 30 to the outer face of the base. The ports 34 are substantially tangential to the pocket 30 and diverge outwardly as shown in Fig. 2. In the base 24 are provided chambers 35 connected to the pocket 30 and substantially tangential thereto. The base 24 is secured to the bottom of the casing by bolts (not shown) passed through ears 36 and 37 on base and casing respectively.

The casing 25 includes a column 40 which surrounds the shaft 21 and tubes 41 which register 45 at their lower ends with the enlarged outer portions of the chambers 35. The tubes 41 are connected by the cross-rib 28 which has at its center a sleeve 42 for the shaft 21 and in which the bearings 27 are mounted. The tubes are also 50 connected by base plates 43 which rest upon the wall 31 of the base and close the tops of the ports 34. The plates 43 are spaced from the rib 28 and collar 42 to provide openings 44 to the pocket 30.

The column 40 of the casing 25 is enlarged at 55

vertically separated points to form chambers 45, here shown (see Fig. 7) as annular, into the lower one of which the tubes 41 lead. Each chamber 45 is enlarged at the top and provided with a plurality of openings 46. Preferably the wall 47 forming the top of each chamber is inclined downwardly and outwardly, and the openings 46 are formed at right angles thereto. As here shown the openings vary in size, the set at the bottom chamber being the smallest and the set at the upper chamber being the largest, but the sizes of the openings may all be the same or may be otherwise varied, depending upon the material treated or the treatment desired.

15 The impeller 22 comprises a disk 50 having on its upper and lower faces arcuate vanes 51 and 52 leading inward from the periphery and a collar 53 by which the impeller is attached to the shaft 21.

20 As shown in the drawing the elements of the casing are integral parts thereof. If desired, however, the elements might be separately formed and fixed in position in any suitable manner, or the casing might be made of two half sections removably connected along a midcentral vertical plane. The motor and casing are movable as a unit and the casing is provided with a handle bar 55 by which the unit can be easily manipulated.

25 In using this mixer to agitate the liquid contents of a barrel or other container it is placed vertically in the container with the legs 33 resting upon the bottom thereof. The rotation of the impeller 22 by the motor 23 creates the following agitation. The liquid is drawn by the impeller through the openings 32 and 44 into the pocket 39 of the base and ejected thereby from the pocket through the ports 34 directly into the container and through the chambers 35 into the tubes 41. The streams leaving the base through the ports 34 set up a swirling or spiral movement in the liquid at the bottom of the container, thus breaking up any thickened sediment or masses and ensuring that portions at least of the thickened mass should enter the pocket. The cross-rib 28 acts not only to support the collar 42 but also acts upon the swirling liquid to break up any inverted vortex that might be set up and to cause the liquid to enter the pocket 30 through the openings 44.

30 The liquid forced by the impeller into the chambers 35 escapes therefrom through the tubes 41 into the column 40 of the casing 25 and the several chambers 45. A portion of the liquid entering each chamber is returned to the main body in the container through the openings 46, leaving in the form of spouts, indicated on Fig. 1.

35 The movement of the liquid thus set up is continued until the contents of the container are substantially uniform and homogeneous. As the liquid set in circulation is drawn from the bottom of the container, it is of course replaced by liquid from the upper levels. It will be noted that the impeller 22 has vanes on its upper and lower surfaces and that, since the mouths of the chambers 35 are both below and above the body of the impeller, liquid is forced into the chambers by both sets of vanes, whereas the mouths of the ports 34 are above the body of the impeller so that liquid is forced into the ports by the upper set of vanes alone. In the drawings are shown four ports 34 and two diametrically opposite chambers 35. This arrangement has been found to give satisfactory service, but it 40 will be understood that the invention is not limited thereto and that other arrangements may be made if desired.

45 It will be noted that the spaces between the vanes 51 and the plate 43 and between the vanes 52 and the bottom wall of the pocket 30 are narrow and consequently the particles of the liquids are broken up as they enter the pocket. This breaking up of the particles is further carried out by the centrifugal force developed by the impeller.

50 When heavy non-diffusible liquids are being mixed it is most important that the openings 46 be arranged as shown in the drawings. Thereby the greater quantity of the liquid is raised in the column 40 to the upper row of openings 15 before being returned to the container. For example, if the area of the upper row of openings 46 be four times as large as that of the other openings combined and the container have a capacity of fifty gallons the mixer is capable of handling twenty-five gallons per minute of which twenty gallons are returned through the upper row of openings alone, and will form a layer on the top of the mass of liquid. Thus in the course of two minutes all the liquid is 25 passed through the mixer. Should, on the other hand, the device be used primarily as an agitator it is of advantage that all the openings be of the same size so that the disturbing action of the liquid discharged from the column be uniformly distributed throughout the container.

30 Since the liquid in the column 40 rises out of contact with the main body of liquid the friction loss is held at a minimum much lower than that in mixers where an open stream is projected upwardly through the mass to be mixed. Thus the operating cost of a mixer embodying this invention is very low, the motor employed being at least one-half the size of the motor employed in the form of mixer mentioned above.

35 Fixed to the column 40 of the casing 25 above the upper chamber 45 is a splash plate 56 which prevents the liquid sprayed through the openings 46 of the upper chamber from leaving the container or from wetting the operator.

40 Lest the circulation set up be such, due, for example, to the speed of the impeller, the formation of a vortex by the shaft, or the fluidity of the liquid, that liquid rises in the casing beyond the upper chamber, suitable means are provided to prevent the escape of the liquid from the top of the casing. Thus in the construction shown in Fig. 1 the casing 25 is provided with a sleeve 60, here shown as integral with the column 40, which encloses the shaft 21 and leads into a pocket 61. Fixed to the shaft 21 is an impeller 62 which is mounted in the mouth of the pocket 61. An annular disk 63 which extends across and closes the pocket 61, rests upon and is fixed to a shoulder 64. Should liquid rise through the space between the shaft 21 and the sleeve 60 and enter the pocket 61 it will be forced back down the column by the pressure created by the impeller 62 and prevented from escaping past the disk 63.

45 Fig. 8 illustrates the top of a similar device wherein other means for preventing the escape of the liquid from the top of the casing 25 are provided. The device here shown is particularly adapted for agitating hot liquids in a closed kettle, the flange 70 in the casing 25 serving to fix the device to the kettle (not shown) and to close the mouth thereof. Liquids so treated possess particular penetrating power and hence it has been found desirable to provide a stuffing box 75

71 for the shaft to prevent the escape of the liquid. The box 71 includes packing 72 between the shaft 21 and a sleeve 73 and a locking ring 74 which is adjustably attached to the shoulder 64 and by which the packing is held in the proper condition.

In Fig. 9 is shown still another form of means by which the escape of liquid is prevented. Near the upper end of the casing 25 is provided a sleeve 80, here shown as integral with the casing, having an annular pocket 81 and a passage 82 through which the shaft extends, and in which may be inserted a sleeveless bearing (not shown). Between the sleeve 80 and a disk 83 fixed to the shoulder 64 of the casing above the sleeve is formed a chamber 84 into which liquid rising in the casing is conducted by the pocket 81 and passage 82 past the shaft 21. Leading from the pocket 81 to the outer surface of the casing is a port 85. A similar port 86 leads from the chamber 84 through the sleeve 80. Thus any liquid that might rise in the casing during the operation of the device is returned to the container through the ports 85 and 86. The mouths of the ports 85 and 86 are usually, as here shown, directed downwardly so that the liquid will flow out under the force of gravity and no splash plate be required. Should, however, conditions arise under which the liquid has considerable head, the ports might be directed upwardly, in which case a splash plate will probably be necessary.

The device shown in Fig. 10 differs from those previously described in that it is particularly adapted for use with liquids containing sand, emery, or other abrasive material. The structure of the device is in general like that of the devices previously described and the corresponding elements will not be described but will be designated in the drawing and referred to herein by the same reference characters.

The particular feature which distinguishes this device from those previously considered is the provision of a stationary tube 90 which encloses the shaft 21, being supported at the bottom in a rib 91 integral with the casing 25 and at the top in a sleeve 92 having a flange 93 which rests upon the shoulder 64. Packing 94 clamped in a recess 95 of the sleeve 92 by a locking ring 96 prevents the passage of liquid beyond the sleeve. Ports 97 similar to ports 46 and 85 and leading from a chamber 98 below the sleeve 92 return to the container any liquid which has risen above the upper chamber 45. The shaft 21 is supported adjacent its lower end by a bearing 99 secured to the rib 91.

Figs. 11, 12, 13 and 14 illustrate another embodiment of this invention in which the device, instead of being insertable as a unit into a container, is assembled with and forms a part of a container. Supported by a pedestal 100 is a base 101 to which is secured a wall 102, the base and wall forming a container for the liquid to be agitated. The center portion of the upper surface of the base 101 is in general similar to the base 24 of the embodiments previously described. The base 101 includes a wall 103, ports 104 and chambers 105 which correspond in function and structure to the wall 31, ports 34 and chambers 35. An impeller 106 comprising a disk 107 provided with vanes 108 at upper and lower surfaces is mounted for rotation within a central pocket 110 defined by the wall 103. A sleeve 111, projecting downwardly from the disk 107 through an opening 112 in the bottom of the pocket 110,

is fixed to the shaft 113 of a motor 114 supported in any suitable manner as by the pedestal 100.

Fixed to the base 101 is the liquid distributing unit 115 comprising a tubular casing 116 closed at the top, and a pair of tubes 117 leading from the base of the casing and adapted, when the unit 115 is properly positioned, to register with the chambers 105 of the base. The unit 115 is here shown as made into two half sections adapted to be removably assembled by suitable means as, for example, the clamps 118. The unit 115 is mounted upon the base 101 in any desired manner and is here shown secured by nut and bolt assemblies 119 passed through overlapped ears 120 of the unit sections and through holes in the base 101. Through the wall of the casing are formed openings 121 arranged in vertically spaced rows. Preferably the size of the openings in the rows is graduated, the smallest being in the lowest row and the largest being in the top row.

The unit 115 includes a ring 122 which, when unit and base are properly assembled, rests upon the wall 103 and extends over the vanes 108. Ribs 123 on the unit sections abut (see Fig. 13) over an opening 124 bounded by the ring 122. At the under side of the base 101 is provided an annular rib 125 which encloses a pocket 126 and to which is removably secured a downwardly projecting sleeve 127 which surrounds the sleeve 111 of the impeller. Mounted upon the sleeve 111 and rotated thereby is a collar 128 having an annular tongue 129 which enters a similar groove 130 in the sleeve 127. Escape of liquid from the pocket 126 is prevented by a spring packing 131 in an annular recess 132 in the sleeve 127 which acts on a rib 133 on the collar 128.

Upon the rotation of the impeller 106 in the pocket 110 the liquid in the container is agitated in substantially the same manner as is the liquid in the containers previously described. Liquid drawn through the opening 124 into the pocket 110 is ejected through the ports 104 and into the chambers 105. The streams of liquid from the ports 104 set up a swirling, whirling motion at the bottom of the container. The liquid entering the chambers 105 is forced up through the tubes 117 into the casing 116 and escapes from the casing through the openings 121 into the container. The liquid leaves the casing in the form of streams under appreciable pressure and thus acts not only to replace the liquid at the higher levels with liquid from the lowest level, but also to agitate the liquid and thus ensure uniformity.

While the packing 131 normally prevents escape of liquid from the pocket 126, it has been discovered that when the device is operated the rotation of the collar 128 by swirling the liquid varies its pressure to such an extent that some will escape past the packing. As a further protection, therefore, vanes 135 are formed on the under face of the collar at the periphery (see Fig. 14), which vanes oppose the entry of the liquid.

The ribs 123 act, like the cross-rib 28, as a barrier to break up the inverted vortex formed by the whirling of the liquid and ensure its entry into the pocket 110 through the opening 124.

It will be noted that the unit 115 is not only demountably assembled with the base 101 but is also made in two sections so that it can be easily cleaned. The casing 25 of the other embodiments may, if desired, be similarly constructed.

While certain embodiments of this invention

have been shown and described in detail, it will be understood that the invention is not limited thereto and that changes in such embodiments as well as other embodiments thereof may be made without departing from the spirit and scope of this invention as set forth in the following claims.

I claim:

1. A mixer by which liquid in a container is agitated, comprising a base having a pocket therein and a casing connected to said base, an impeller in the pocket of the base, ports connecting the container and the pocket, passages in the base leading from the pocket and terminating in chambers, said casing including a column extending into the container and tubes connecting said column with said chambers, said column having openings through the wall thereof leading into the interior of the container, and means for rotating said impeller whereby liquid drawn into the pocket from the container is in part discharged through the ports into the container and is in part driven through said chambers and said tubes into said column and thence through the openings therein into the container.
2. A mixer by which liquid in a container is agitated, comprising a base having a pocket therein and a casing connected to said base, an impeller in the pocket of the base, ports connecting the container and the pocket, passages in the base leading from the pocket and terminating in chambers, said casing including a column extending into the container and tubes connecting said column with said chambers, said column having vertically spaced chambers therein, and openings in the walls of said chambers leading into the interior of the container, and means for rotating said impeller whereby liquid drawn into the pocket from the container is in part discharged through the ports into the container and is in part driven through the chambers in the base and said tubes into said column and the chambers therein and thence returned to the container through the openings in said last-named chambers.
3. A mixer by which liquid in a container is agitated, comprising a base having a pocket therein and a casing connected to said base, an impeller in the pocket of the base, ports connecting the container and the pocket, passages in the base leading from the pocket and terminating in chambers, said casing including a column extending into the container and tubes connecting said column with said chambers, said column having vertically spaced chambers therein and openings in the wall of said chambers leading into the interior of the container, said openings being graduated in size, the set in the bottom chamber being the smallest and the set in the top chamber being the largest, and means for rotating said impeller whereby liquid drawn into the pocket from the container is in part discharged through the ports into the container and is in part driven through the chambers in the base and the tubes into said column and the chambers therein and thence returned to the container through the openings in said last-named chambers.
4. A mixer by which liquid in a container is agitated, comprising a base having a pocket therein and a casing connected to said base, an impeller in the pocket of the base, ports connecting the container and the pocket, passages in the base leading from the pocket and terminating in chambers, said casing including a column

extending into the container and tubes connecting said column with said chambers, and having openings through the wall of said column into the interior of the container, a shaft extending through the column of the casing and connected to said impeller, and means for rotating said shaft and the impeller connected thereto whereby liquid drawn into the pocket from the container is in part discharged through said ports into the container and in part driven through the chambers and said tubes into said column and thence returned to the container through the openings in said column.

5. A mixer by which liquid in a container is agitated, comprising a base having a pocket therein and a casing connected to said base, an impeller in the pocket of the base, ports connecting the container and the pocket, passages in the base leading from the pocket and terminating in chambers, said casing including a column extending into the container and tubes connecting said column with said chambers, and having openings through the wall of said column into the interior of the container, said openings being arranged vertically along the column and graduated in size, the smallest opening being the lowest and the largest opening being the highest, and means for rotating said impeller whereby liquid drawn into the pocket from the container is in part discharged through the ports into the container and is in part drawn through said chambers and said tubes into said column and thence through the openings therein into the container.

6. In a mixer by which liquid in a container is agitated which includes a base having therein a pocket open to the container and a casing connected to the base, an impeller rotatable in said pocket, said impeller comprising a disk and arcuate vanes on the upper and lower faces of the disk, passages in said base leading from the pocket therein and terminating in chambers, tubes connecting said chambers with said casing and means for rotating said impeller to draw liquid from the container into the pocket and force such liquid into said chambers and through said tubes into said casing.

7. In a mixer by which liquid in a container is agitated which includes a base having therein a pocket open to the container and a casing connected to the base, an impeller rotatable in said pocket, said impeller comprising a disk and arcuate vanes on the upper and lower faces of the disk, passages in said base leading from the pocket therein and terminating in chambers, tubes connecting said chambers with said casing and means for rotating said impeller to draw liquid from the container into the pocket and force such liquid into said chambers and through said tubes into said casing, ports leading from said pocket into the container, said ports being in direct communication with the vanes on one face only of the impeller disk and said passages being in direct communication with the vanes on both faces of such disk.

8. A mixer by which liquid in a container is agitated including a column having openings in the wall thereof, an impeller by which liquid is drawn from the container and forced to rise in said column and return to the container through the openings in the wall of the column, a shaft extending through the column, to which the impeller is secured, means for rotating the shaft and the impeller secured thereto, the top of the column being open and the shaft passing

through the open top, and means for preventing liquid rising in the column above the openings from escaping from the top of the casing, said means including a sleeve which surrounds the shaft and defines an annular passage therewith, a collar fixed on the shaft above said sleeve, and

a disk carried by the collar and resting upon the column, said sleeve, disk and collar defining a pocket closed at the top by said disk and collar which receives any liquid that has risen through the passage defined by the sleeve and shaft.

EDWARD SCHMIDT.

5
